ATTACHMENT FOR STAPLING MACHINES

Filed June 11, 1929

FIG. 1.

FIG. 2.

FIG. 3.

INVENTOR
Lou OBSTFELD
BY Edwin Lerieth

ATTORNEY

UNITED STATES PATENT OFFICE

LOU OBSTFELD, OF BROOKLYN, NEW YORK

ATTACHMENT FOR STAPLING MACHINES

Application filed June 11, 1929. Serial No. 370,052.

This invention relates to attachments for stapling machines of the small hand type and has reference particularly to a gripping jaw pivotally connected to the stapling machine and adapted to take hold of materials to be stretched and tacked so as to bring the same in the path of the staples which are driven by the machine.

The type of stapling machine to which the present invention is particularly applicable is commonly used for tacking signs in place, fixing the wire mesh of screens in position on their frames or in other capacity where the article or material being mounted must be held in stretched condition during the tacking process.

It is the object of my invention to provide means carried by any of the well known types of hand stapling machines for gripping the material, being mounted, between the base plate of the machine and a movable jaw whereby the latter is capable of firmly engaging the material while it is being stretched and fastened down by a staple.

The present invention has the advantage, due to its special construction of enabling the operator to hold the stapling machine in one hand against an upright surface, while manipulating the gripping jaw with the same hand, thus leaving the other hand free to drive the staple.

I accomplish these objects by means of the device hereinafter described and claimed and illustratively exemplified in the accompanying drawings in which, Figure 1 is a side elevational view of a stapling machine equipped with the clamping jaw; Figure 2 is a front elevational view of the same with the jaw open; and Figure 3 is a perspective view of the jaw separated from the machine.

Referring to the drawings, 10 denotes the frame of a hand stapling machine which consists of the base and magazine section 11, hand grip 12 disposed substantially parallel to the magazine and spaced therefrom directly over the latter, as illustrated in Figure 1. The magazine 11 and hand grip 12 at their forward end are an integral part of an upright portion 13 designed to support and guide the hammer 14. The hammer 14 is

provided with a downwardly projecting end portion 15 which engages the closed end of the staple and upon depression of the hammer drives the staple through a guideway 16 into the underlying surface. 55

The under surface of the base or magazine section 11 is perfectly flat up to the point where the guideway 16 begins, the point being rearwardly of the path of the staple. The under surface at this point and 60 for a short distance rearwardly thereof forms a fixed jaw 17. Pivotally mounted on a pin or screw 18 carried on one side of the magazine 11 is the movable jaw member 19, which comprises a strip of steel having an 65 upright portion movable along the side of the base and handle members 11 and 12, a jaw portion 20 bent at right angles to the upright portion and projected underneath the fixed jaw 17, and a lever portion 21 bent at 70 substantially right angles to the upright portion and in a direction rearwardly of the machine, so as to overlie the grip 12 and enable the operator with one hand to grip the handle 12 and at the same time press downwardly on lever 21 to close the movable jaw 20 against the fixed jaw 17. The jaw is normally held in open position by a spring 22 which is coiled about a screw 23 in the side 75 of the base and which has one end engaged 80 against the upright portion of the jaw member 19 and the other end anchored in the base 11.

In the operation of the device, the material A to be attached and stretched is disposed at its edge between the jaws 17 and 20 and the lever end 21 depressed by the hand gripping the handle 12 as illustratively exemplified in Figure 1. This operation closes the jaw 20 and the material is thus firmly gripped and may be moved about or stretched as desired. Having properly located the portion of the material to be attached the hammer 14 is depressed by a blow from the other hand which drives the staple through the stretched material just in front of the portion gripped between the jaws. 95

Having now described my invention what I claim and desire to secure by Letters Patent is: 100

1. In a stapling device having an upright staple driving arrangement, a lateral base portion and hand grip spaced thereover, the combination of gripping means mounted on the device and having a jaw portion operating under the base, and a lever projecting over the hand grip whereby the stapling device may be held and gripping means operated in the same hand.
- 10 2. In combination with a hand operated stapling device, comprising an upright hammer, a base section to rest against the work and a hand grip spaced over the base section, a lever member pivotally mounted on the base section and having a jaw portion movable against the under side of the base rearwardly of the path of the staples driven by the hammer, and a grip portion projecting rearwardly over the hand grip.
- 15 20 In testimony whereof he has affixed his signature.

LOU OBSTFELD.
